(57) **CLAIM**

The ornamental design for a muscle scraper, as shown and described.

DESCRIPTION

FIG. 1 is a first perspective view of a muscle scraper embodying the claimed design;

FIG. 2 is a second perspective view thereof;

FIG. 3 is a first side view thereof;

FIG. 4 is a second side view thereof;

FIG. 5 is a front side view thereof;

FIG. 6 is a back side view thereof;

FIG. 7 is a top side view thereof; and,

FIG. 8 is a bottom side view thereof.

The broken lines in the drawings depict portions of the muscle scraper in which the design is embodied that form no part of the claimed design.

1 Claim, 8 Drawing Sheets
